Des. 208,391
Patented Aug. 22, 1967

208,391

COFFEE MAKER

Leonard P. Hausam, Minneapolis, Minn., assignor to
Charter Design and Manufacturing Corporation, Min-
neapolis, Minn., a corporation of Minnesota

Filed June 22, 1966, Ser. No. 2,778

Term of patent 14 years

(Cl. D94—3)

FIG. 3

FIG. 4

FIG. 5

FIG. 6

FIG. 1 is a front perspective view of a coffee maker, showing my new design;

FIG. 2 is a rear perspective view of the coffee maker;

FIG. 3 is a top plan view;

FIG. 4 is a front elevation;

FIG. 5 is a side elevation; and

FIG. 6 is a rear elevation.

The essential features of the design reside in the full line portions of the drawings.

I claim:

The ornamental design for a coffee maker, substantially as shown and described.
